UNITED STATES PATENT OFFICE.

BASCOM J. BROWN, OF ENSLEY, ALABAMA.

WATCH-WINDING CHUCK.

Application filed June 10, 1920. Serial No. 387,812.

To all whom it may concern:

Be it known that I, BASCOM J. BROWN, a citizen of the United States of America, residing at Ensley, in the county of Jefferson and State of Alabama, have invented 5 certain new and useful Improvements in Watch-Winding Chucks, of which the following is a specification.

This invention relates to a watch maker's 10 tool especially adapted for winding all sizes of watches. At the present time watch makers and repairers are required daily to wind the watches on hand and this involves a very considerable waste of time and 15 energy.

The object of this invention is to provide a very simple and inexpensive chuck or tool adapted to be inserted in the watch maker's lathe and which carries a rubber 20 or friction pad of such shape and dimension as to receive the various sizes of watch crowns and to frictionally grip same so that the crown is turned with the chuck and the watch thus mechanically wound.

It is of especial importance in connection 25 with my invention to note that the watch maker skilled in the art can by hand so regulate the frictional engagement between the crown and the friction pad of the chuck as to insure slippage when the spring is 30 sufficiently wound. In this way the watches with the longest springs and small wrist watches with lightest springs can all be wound with the same device and without 35 danger of breaking the spring.

While it is understood that my invention may be variously constructed, I have illustrated in the accompanying drawings what I regard as the preferred embodiment of 40 the same.

As illustrated in the drawings:—

Fig. 1 shows the chuck in side elevation with a watch crown pressed thereagainst for the purpose of winding the watch.

Fig. 2 is an end view of the chuck; and

Fig. 3 is a detail sectional view through the friction pad.

Fig. 4 is a cross-sectional view through the chuck clamp showing the rubber pad in 50 elevation.

Similar reference numerals refer to similar parts throughout the drawings.

The chuck comprises a body member 1 having a shank 2 adapted to fit into the ordinary watch maker's lathe. The body 55 has a knurled rim 3 and within is threaded to receive the threaded extension 4 on the chuck member 5, which is provided with a knurled rim 6. This chuck member 5 is provided with an enlarged annular opening 6 at its outer end through which projects the concave working face 7 of a friction pad 8 which is held in the chuck by being clamped between the members 1 and 5 and which may be made of rubber or any 60 suitable friction material. The concave working face of the rubber pad is concentric with the axis of the chuck shank 2 and is wide enough to accomodate the largest 65 watch crowns. The concave working face 70 gives the most satisfactory frictional engagement with the crowns of different sizes that may be fitted thereinto.

Having assembled the chuck in the lathe and started the lathe, the watches are 75 wound as fast as they can be picked up and their crowns pressed to the rapidly rotating friction pad. When the spring is sufficiently wound its resistance causes the crown to slip, thus automatically protecting the 80 spring. The friction pads are inexpensively and readily replaceable so that the life of the tool is indefinite. The type of the friction pad holder may be widely varied and the construction and material of the friction 85 pad itself may be changed to meet the different conditions, but I have obtained best results from a soft rubber pad.

Without intending to limit myself to the specific details of construction described, 90 what I claim as new and desire to secure by Letters Patent, is:—

1. A watch winding tool comprising a chuck having a shank adapted to fit into a watchmakers lathe and having a socket, 95 a rubber friction pad mounted in said socket and having in its outer end a deeply indented cone shaped seat, the axis of which is in alignment with the axis of the shank, and demountable means to clamp said pad in 100 said chuck socket.

2. In a watch winding tool, a chuck having a shank adapted to fit into a watchmakers lathe, a recess in the outer end of

said chuck, a rubber friction pad having its base adapted to fit into said recess and having a reduced outer end formed with a deeply indented cone shaped socket disposed with its axis in alignment with the axis of the shank, and a screw sleeve adapted to slip over the indented end of the pad and to have threaded engagement with the

chuck to clamp the pad base firmly in said recess, substantially as described. 10

In testimony whereof I affix my signature.

BASCOM J. BROWN.
